CLAIM

The ornamental design for an electric motorcycle, as shown and described.

DESCRIPTION

FIG. 1 is a perspective view of an electric motorcycle showing our new design;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top plan view thereof.

The broken lines shown herein are for the purpose of illustrating portions of the electric motorcycle and form no part of the claimed design.
